UNITED STATES PATENT OFFICE

GEORGE E. PRENTICE, OF BERLIN, CONNECTICUT, ASSIGNOR TO G. E. PRENTICE MANUFACTURING COMPANY, OF NEW BRITAIN, CONNECTICUT, A CORPORATION OF CONNECTICUT

SLIDER FOR FASTENERS

Application filed October 16, 1929. Serial No. 399,954.

This invention pertains to fastening devices of the class commonly known as separable, interlocking fasteners of which the patent to Judson, No. 557,207, dated March 31, 1896 may be cited as an early instance. Such devices are commonly employed for closing gaps or openings in garments, for example, sweaters, coats, leggings, overshoes as well as for closing bags, packages, tent flaps, automobile curtains and many other articles.

Usually the complementary series of fastener elements at the opposite edges of the gap are brought into cooperating relationship by means of a slider having suitable cam-like guides properly shaped for the purpose. However, it has been recognized since as early at least as the Judson patent above referred to, that if the cam elements of the slider are of such slope as to insure ease of operation, the slider may slip lengthwise of the closed fastener in response to stresses tending to open the gap, thus allowing the gap to open inadvertently, unless some means be provided for positively holding the slider at the limit of its travel with the gap closed. In the Judson patent referred to, a crude form of retaining means comprising loops adapted to engage appropriate pins was provided for the purpose and since the Judson patent, many other retaining devices have been proposed.

Since rapidity of actuation is one of the important advantages claimed for fasteners of this type, it is obvious that any retaining means requiring careful manipulation by the operator detracts from the value of the device, and for this reason, attempts have been made to embody the retaining means in the actuating pull or tab in such a way that when the pull or tab is released after actuation of the slider and allowed to hang vertically down, the slider is automatically retained in position.

In one very desirable construction known to me, a slider, which in most respects is of a usual type, has an opening in its front wing in which a friction member is loosely fitted and the pull tab has an offset or cam at its inner side so arranged that when the pull hangs downwardly from one end of the slid-

er, the cam or offset forces the friction member inwardly through the opening so that it presses against the fastener elements, thus preventing accidental movement of the slider, but in this prior construction, if for any reason the slider be inverted so that the pull tab hangs downwardly from the other end of the slider, the cam element of the pull tab is no longer effective to actuate the friction member.

However, in some garments or other articles, the gap is closed by movement of the slider upwardly, while in other instances, the gap is closed by downward movement of the slider. Since the pull tab tends to hang downwardly in either case when released by the operator it has previously been necessary in constructing sliders of the type just referred to, to design the pull and retaining means with particular reference to the direction of movement of the slider in closing the gap, and thus a garment manufacturer who used fasteners, some of which closed by upward and others by downward movement of the slider, has been obliged to provide himself with sliders of two distinct forms.

In accordance with the present invention, I provide a slider having a very simple, inexpensive and reliable form of pull controlled retaining means which will retain the slider in adjusted position with the pull depending upwardly or downwardly in closing the gap.

In the accompanying drawings I have illustrated a preferred embodiment of my invention by way of example

In the drawings:

Fig. 1 is a fragmentary front elevation, to large scale, illustrating a fastener of the type referred to provided with a slider embodying the present invention;

Fig. 2 is a vertical section substantially on the line 2—2 of Fig. 1 showing the parts positioned to retain the slider in adjusted position, certain of the fastener elements being shown in section but omitting the stringers;

Fig. 3 is a section similar to Fig. 2 but indicating the position of the parts suitable for actuation of the slider for closing or opening the gap;

Fig. 4 is a fragmentary diagrammatic view to smaller scale illustrating the use of the improved slider in closing gaps by movement of the slider upwardly or downwardly respectively;

Fig. 5 is a plan view to large scale of a blank suitable for use in forming the slider body herein illustrated;

Fig. 6 is a composite view showing in front and side elevation a suitable form of pull or tab useful in actuating the slider of Figs. 1 to 3;

Fig. 7 is a plan view to large scale of a blank useful in the preparation of the friction device forming a part of the invention;

Fig. 8 is an edge elevation of the friction device completed; and

Fig. 9 is a view similar to Fig. 3 illustrating the locking action when the slider occupies the position shown at the lower part of Fig. 4.

Referring to the drawings I will first describe one desirable form of slider provided with a retaining shoe engageable with the fastener elements and will then describe my improved means for actuating the shoe, such means being so designed as to permit use of the same slider for closing the gap either by upward or downward movement of the slider. Referring particularly to Figs. 1 to 3, the numerals 1 and 2 designate tapes or stringers to which the opposed series of fastener elements 3 are respectively connected. While it is usual to furnish fasteners of this kind to the trade in the form of a complete structure comprising the tapes or stringers upon which the series of fastener elements are mounted, it is to be understood that so far as its broader aspects are concerned the present invention is not necessarily limited to the inclusion of these tape members, since it is conceivable that the fastener elements might be applied directly to the edges of the material in which the gap occurs and when in the appended claims the term "stringer" is employed, it is to be understood as broadly comprehending any flexible element forming in effect one edge of the gap to be closed. For convenience in illustration I have shown the fastener elements 3 as of the type more fully described and claimed in the patent to Prentice and Legat No. 1,658,392, dated February 7, 1928, but it is to be understood that the present invention is not to be limited to such specific use but is applicable to fasteners of other types falling within the general class.

For use in moving the fastener elements of the opposed series into operative relationship, I employ a slider S which in general may be of a type well known in the art as, for example, that shown in the patent to Prentice No. 1,677,408, July 17, 1928, although I have here illustrated the slider as of specifically novel form and construction.

Thus, my improved slider comprises the front wing 4 (Fig. 2) and the rear wing 5 united by the neck 6, and this slider body may be formed conveniently from a unitary piece of sheet metal shaped to provide the blank shown in Fig. 5. This blank comprises the wing portions 4^a and 5^a integrally united by the neck 6 and having the elongate guide tongue 7 projecting integrally from the outer end of the wing portion 4^a. This elongate guide tongue 7 is provided near its free end with a portion 8 of reduced width, beyond which the extremity 9 of the tongue again increases in width. The neck 6 is provided at its opposite edges with integral tabs 10 and 11 and it is to be understood that, as usual, in the manufacture of sheet metal sliders, the lateral edges of the wing portions 4^a and 5^a are bent inwardly to form suitable guide flanges. The blank, as shown in Fig. 5, is bent at the junctions of the wing members with the neck so as to bring the wing portions into substantially parallel relation, and the guide tongue 7 is then bent to provide the lower substantially horizontal portion 12 (Fig. 2), the substantially vertical guide portion 13 which is parallel to and spaced from the front surface of the wing 4, and the top member 14 which extends rearwardly across the top of the slider. The reduced portion 8 of the tongue is disposed between the tabs 10 and 11 which are turned upwardly and then inwardly as indicated in Fig. 1 so as to clamp the end portion of the tongue between them.

The front wing 4 is provided with an opening 15 for the passage of the friction shoe 16. This friction shoe is conveniently formed as an integral U-shaped bend in a sheet metal rocker member comprising the divergent stiffly resilient arms 17 and 18. This rocker may be made from a piece of sheet material of the general shape indicated in Fig. 7 having the central neck portion 16^a of such width that when bent to the shape shown in Fig. 8 it may pass through the opening 15. This blank also comprises the end portions 17^a and 18^a of greater width than the neck and adapted to form the arms 17 and 18. Preferably the outer ends of these arms are recessed or forked to provide the retaining fingers 19 which engage the opposite edges of the guide member 13 in order to hold the rocker in properly assembled relation to the slider body. The pull or tab 20 is here shown as of a general type commonly employed in sliders of this kind and is preferably made from sheet material of any suitable character.

My present invention relates to improvements upon the slider thus far described. In accordance with the present invention the tab or pull is preferably of more or less T-shape in edge elevation as shown in Fig. 6, the cross arm of the T being formed by suitably bending or swedging the upper edge of the sheet

material forming the body of the pull. Thus, as shown in this figure, the pull proper 20 is provided with the oppositely and laterally projecting portions 21 and 22 which collectively form the crossbar of the T-shaped pull.

The pull is provided with an opening 23 through which the guide member 13 passes, the guide and opening supporting the pull pivotally and permitting the pull to be moved from one end to the other of the slider. As indicated in Figs. 2 and 3 the cross bar of the pull is disposed between the front face of the rocker and the rear face of guide 13. When, as shown more particularly in Fig. 3, the pull is swung outwardly at a substantial angle to the direction of movement of the slider in order to facilitate actuation of the latter, the crossbar comprising the members 21 and 22 moves freely in the space between the guide 13 and the rocker so that the position of the rocker is not effected substantially by the pull, thus permitting the shoe 16 to retreat from the opening 15 and preventing any substantial pressure of the shoe against the fastener elements so that the slider can be moved freely in either direction. Assuming that the slider is moved upwardly to close the fastener, as shown at the upper part of Fig. 4, the pull 20, when released by the operator, will hang downwardly from the lower end of the guide 13, the weight of the pull tending to swing it to a substantially vertical position. Since the crossbar comprising the members 21 and 22 is of substantial width, the vertically depending pull causes the ends of the bar to contact respectively with the guide 13 and with the lower arm 17 of the rocker, and the crossbar thus acts as a cam for forcing the arm 17 against the wing 4. By reason of the divergent arrangement of the arms 17 and 18 the end of the arm 18 now bears resiliently against the inner surface of the guide 13 which forms a slightly resilient abutment, and the pressure of the crossbar of the pull against the lower arm 17 causes the shoe 16 to project through the opening 15 and press forcibly against the fastener elements, pushing them against the rear wall 5 of the slider and exerting a frictional drag which effectively prevents accidental movement of the slider. To assure the maintenance of this locking or holding action the pull 20 may be swung rearwardly by pressure of the fingers toward the plane of the wing 4 (with reference to the pivotal support of the pull upon the guide 13) so that the crossbar, comprising the parts 21 and 22 will assume an inclined position. In thus pressing the pull rearwardly, the rocker arms 17 and 18 as well as the guide 13 may spring slightly, being formed of resilient material, and thus when the pull is disposed in its rearward position, as described, the pressure of the parts will so retain it until it is positive-

ly swung forwardly beyond the vertical plane.

Since the crossbar of the pull is substantially symmetrical, that is to say, projects to both sides of the plane of the part 20, the pull will operate in the same way for pressing the friction shoe into operative engagement with the slider elements whether the slider be disposed as shown in Figs. 2 and 3 or whether it be reversed as shown at the lower part of Fig. 4. Thus our improved slider may be used with the same locking or holding effects in closing gaps either by upward or downward movement. For example, in children's draw leggings, the gap in the body portion is usually closed by a slider which moves upwardly, while the gaps in the legs are closed by sliders which move downwardly. By employing the slider above described, the manufacturer of such a garment may use like sliders both in the body portion and in the legs of the garment, with the assurance that the sliders will remain in gap-closing position indefinitely until positively moved to open the gap.

While I have illustrated certain desirable embodiments of the invention by way of example, I wish it to be understood that the invention is not to be limited by the arrangements specifically shown and described but is broadly intrusive of such modified constructions as fall within the range of equivalency of the appended claims.

I claim:

1. A slider for fasteners of the kind having stringers carrying series of interengaging fastener elements, said slider being of the kind having front and rear wings and retaining means comprising a shoe fitted loosely in an opening in one of the wings, a pull for moving the slider in either direction, said pull device comprising means cooperable with the retaining means when the pull is at either the lower or upper end of the slider and positioned substantially parallel to the path of movement of the slider, thereby to cause the shoe to engage the fastener elements and retain the slider in position, the slider thus being adapted for alternative use with fasteners which are closed either by upward or downward movement of the slider.

2. A slider for fasteners of the kind having stringers carrying series of interengaging fastener elements, said slider being of the kind having front and rear wings and having retaining means comprising a shoe fitted loosely in an opening in one of the wings and a pull for moving the slider in either direction, said pull having cam elements projecting from its opposite sides for cooperation respectively with said retaining means whenever the pull is disposed at either the lower or upper end of the slider and positioned substantially parallel to the path of movement of the slider, thereby to cause the shoe to engage the fastener elements and retain the

slider in adjusted position whether the slider be used for closing a fastener by upward or by downward movement.

3. A slider for fasteners of the kind having stringers carrying series of interengaging fastener elements, said slider being adapted for alternative use with fasteners which are closed by upward or downward movement of the slider respectively, and comprising a 10 pull for moving the slider, the pull normally depending from that end of the slider which for the time being is the lower end, retaining means actuatable by the pull, while so depending, for retaining the slider in adjusted position, said means comprising a friction shoe fitting loosely in an opening in the slider wall and engageable with the fastener elements to retain the slider in adjusted position, means on the pull cooperable with the retaining 15 means when the pull is at either the lower or upper end of the slider for locking the slider in any position of its travel.

4. A slider for fasteners of the kind having stringers carrying series of interengaging fastener elements, said slider being adapted for alternative use with fasteners which are closed by upward or downward movement of the slider respectively, and comprising a 20 pull for moving the slider, the pull normally depending from that end of the slider which for the time being is the lower end, and friction means actuatable by the pull when so depending for retaining the slider in adjusted position, said fastener means comprising a 25 shoe fitting loosely in an opening in the slider wall and a part engageable by the pull when depending from either end of the slide respectively to force said shoe into retaining engagement with the fastener elements, means on the pull cooperable with the retaining 30 means when the pull is at either the lower or upper end of the slider for locking the slider in any position of its travel.

5. A slider for fasteners of the kind having 45 stringers carrying series of interengaging fastener elements, said slider being adapted for alternative use with fasteners which are closed by upward or downward movement of the slider respectively, and comprising a 50 slideable pivoted pull for moving the slider, the pull normally hanging from that end of the slider which for the time being is the lower end, and retaining means for holding the slider in adjusted position, said retaining 55 means comprising a rocker having divergent wings and a central part constituting a friction shoe engageable with the fastener elements to hold the slider in adjusted position, the slider comprising elements engageable 60 with the wings and central part respectively of the rocker for holding the latter in assembled relation to the slider body, the pull having elements cooperable respectively with the wings of the rocker whenever the pull is 65 swung rearwardly with respect to its point

of suspension for causing the retaining means to become and remain operative.

6. A slider for fasteners of the kind having stringers carrying series of interengaging fastener elements, said slider having front and rear wings, the front wing having an opening therein, an elongate guide spaced from the front wing, a rocker having a central part disposed in the opening in the front wing and divergent arms adapted to engage the inner surface of said guide, and a T-shaped pull having an opening for the reception of the guide, the crossbar of the T-shaped pull being interposed between the inner surface of the guide and the rocker and being cooperable with either rocker arm to force the central portion of the rocker against the fastener elements.

7. A slider for fasteners of the kind having stringers carrying series of interengaging fastener elements, said slider having front and rear wings, one wing having an opening therein, an elongated guide spaced from the apertured wing, a rocker having a central part constituting a friction shoe disposed in the opening of said wing and also having divergent arms adapted to engage the inner surface of the guide, a pull movable along the guide, said pull comprising cam elements cooperable alternately with either of the 95 rocker arms for forcing the friction shoe against the fastener elements.

8. A slider for fasteners of the kind having stringers carrying series of interengaging fastener elements, said slider having front and rear wings, one wing having an aperture therein, an elongate guide spaced from the apertured wing, a rocker having a central part constituting a friction shoe disposed in the aperture in said wing, and also having divergent arms adapted alternately to engage the inner surface of the guide, and an actuating device comprising means cooperable 100 alternatively with the respective rocker arms for forcing the friction shoe against the fastener elements, the ends of the rocker having retaining fingers engaging the guide for holding the rocker in assembled relation with the body of the slider.

Signed by me at Waterbury, Conn., this 9th day of October, 1929.

GEORGE E. PRENTICE.
